UNITED STATES PATENT OFFICE.

MORRIS SCHMUCKER, OF LANARK, ILLINOIS.

ATTACHMENT FOR CORN-PLANTERS.

SPECIFICATION forming part of Letters Patent No. 379,821, dated March 20, 1888.

Application filed June 15, 1887. Serial No. 241,331. (No model.)

To all whom it may concern:

Be it known that I, MORRIS SCHMUCKER, a resident of Lanark, in the county of Carroll and State of Illinois, have invented certain new and useful Improvements in Attachments for Corn-Planters; and I do hereby declare the following to be a full, clear, and exact description of the invention, such as will enable others skilled in the art to which it pertains to make and use the same.

The letters of reference in this specification indicate the same parts in all the figures of the accompanying drawings, in which—

Figure 1 is a side elevation of a portion of a planter, showing an ordinary seed-receptacle and shoe with my devices attached. Fig. 2 shows the same in plan after a rotation of ninety degrees to the right. Fig. 3 is an elevation looking to the left in Fig. 1. Fig. 4 is a view, partly in section, showing the construction of certain parts hereinafter referred to.

In the drawings, A B C D represent, respectively, the shoe, discharge-tube, seed-receptacle, and slide-bar of an ordinary corn-planter, 25 of whose frame S T are portions.

In the rear of the receptacle C is placed a box for containing the fertilizing material, and this material is discharged by the action of a rod, D', connected to and moving in unison with the slide-bar D. Below the box is a case, G, communicating with the box and containing a wheel, G', having cups d, whose horizontal shaft is mounted in the side walls of the case. Upon this shaft is fixed a ratchet-wheel, 35 a, Fig. 3, with which engages alternately two spring-pawls, b c, fixed upon the inner faces of a slot in the broadened end of the rod D', which forms a plate, F, to slide in guides F' upon the wheel-case G. By means of this engagement the movement of the bar D' in either direction causes the cup-wheel to rotate from left to right, for as the rod passes back and forth the upper pawl engages the ratchet-wheel in its advance and pushes it from left to right, 45 but springs outward and slips over the teeth on its return. At the same time the lower pawl springs outward and slips over the teeth in advancing, but engages the ratchet and draws it in the same direction—*i. e.*, from left to right—while moving in a contrary direction. 50 From the case G a tube, L L', passes down-

ward and forward to deliver the fertilizer discharged by the cup-wheel between the wings of the shoe A, where it falls with the seed discharged from the receptacle C. As the fertilizer falls from the box E it does not pass directly to the ground, but remains upon an inclined valve-plate, K, until the next movement of the cup-wheel reverses the position of the valve and discharges it with or in point 60 of time a little in advance of the seed, owing to the shortness of the distance through which it at last falls. The valve is centrally pivoted in the tube, and from its upper edge a lug projects through a curved slot in the wall of 65 the tube to engage the lower end of a lever, I, by which the valve is actuated. The lever I is pivoted at J upon the tube, and its upper end passes through an eye upon the lower part of the plate F, which, by its reciprocation, 70 thus carries the lever back and forth.

A clamp, M, is placed upon the rod D', near the box E, and to it is attached a rod, N, which passes horizontally through the box E, and has that part lying within the box bent into 75 loops for agitating the fertilizer just over the wheel, thereby insuring perfect filling of the cups.

The entire fertilizer attachment is secured to the planter by bolts V, passing through the 80 adjacent walls of the box E and seed-receptacle C, and it is adapted for attachment to any planter, whether or not the walls of the seed-receptacle are vertical. The bars P, connecting the slide-bar D and rod D', are adjustable 85 in length to facilitate attachment to any slide-bar. The tube L L' is made in two telescopic sections, as indicated at W, in order that, whatever the height of the particular planter to which it is attached, the fertilizer may be delivered very near the ground, and scattering by wind be thus avoided. 90

What I claim is—

1. The combination, with a fertilizer-receptacle adapted for attachment to the seed-box 95 of a corn-planter, of a peripherally-recessed vertical wheel whose upper side forms the bottom of said receptacle, a band passing from said receptacle to the lower side of said wheel and closely fitting the recessed surface thereof, 100 and a tube open at the top, extending downward from the lowest part of said wheel, where-

by rotation of the wheel may deliver fixed quantities of fertilizer at intervals and through the lower end of said tube.

2. In combination with a fertilizer-receptacle adapted for attachment to the seed-box of a corn-planter, a peripherally-recessed vertical wheel the upper portion of whose circumference forms the bottom of said receptacle, a tube extending downward and forward from the lowest point of said wheel to a point between the wings of the planter-shoe, said tube being provided with a valve near its lower extremity, a ratchet-wheel connected rigidly to said vertical wheel, a slide-bar bearing pawls

adapted to rotate said ratchet-wheel in one direction only, a pivoted lever connecting said slide-bar and said valve, and means for detachably connecting said slide-bar rigidly to the slide-bar of an ordinary planter, substantially as set forth.

In testimony whereof I have signed this specification in the presence of two subscribing witnesses.

20
MORRIS SCHMUCKER.
